UNITED STATES PATENT OFFICE.

CHRISTEL SCHRAUB, OF MAINZ, GERMANY.

DEVICE FOR STOPPING BACK FLASHINGS OF THE FLAMES IN PIPINGS FOR FEEDING GASES OR GAS MIXTURES.

Application filed December 27, 1927, Serial No. 242,928, and in Germany December 29, 1926.

My invention relates to means for preventing or stopping back flashings of the flames and has the object to protect devices and pipings against the danger of fire and 5 explosion.

The known devices arranged hitherto for this purpose in pipes or tubes for feeding gases or gas mixtures comprise an intermediate piece in which either a non-return 10 valve with a safety valve, or a cooling body without a safety valve is arranged, or else protecting nets are provided in the pipings. In case of back flashing of the flame the known non-return valves involve the danger 15 of through-firing either because the inertia of a non-return valve is greater than the rate of ignition of the exploding gases, or because the fresh gases ignite by direct contact with the still burning return gases on 20 re-opening of the non-return valve. This danger of through-firing is not even removed, if a non-return valve, loaded with a heavy spring, is provided which opens only during the suction stroke of the internal 25 combustion engine and by which a permanent smaller weight of charge and therefore a decrease of useful work is obtained only. This latter draw-back in a more or less degree have also all known non-return valves, 30 because their guides restrict the normal cross section of the pipe. In the known cooling bodies and also in the known protecting nets the heated explosion gases have, in case of back flashing of the flame, no other opportunity of expansion and must pass through 35 the protecting device. Cooling bodies and protecting nets have always a limited heat capacity only. Therefore, as a result of constant back flashings of flames which in 40 connection with internal combustion engines are produced by many disturbances, for instance improper composition of the gas mixture, fracture of the suction valves during run a. s. o., the danger exists, that the 45 cooling bodies or protected nets are superheated and the explosion extends further.

According to the present invention the known parts are combined in a new and advantageous manner and known parts are arranged and formed in a new and advantageous manner. So, for instance, protecting nets are provided in a new manner at the joints of the intermediate piece fitted with safety valves, which nets prevent the contact 55 of the igniting flame with the fresh gases in

case of back flashing of flame. Further the guide of the non-return valve is arranged in a new manner in the intermediate piece of great cross section and the spring of this valve is in a new manner so arranged and tensioned that it just supports the weight of said valve; moreover the position of the valve disc may, with regard to the valve seat, be adjusted in a new manner by means of a threaded nipple without affecting the tension of the spring. The valve disc itself is formed in a new manner completely as a cup. By the whole new arrangement is obtained, that no flow resistance during ordinary use occurs, while on back flashing of the flame the latter acts upon the cup of the non-return valve and safely closes the valve. The non-return valve is furthermore by means of its spindle connected to the well known catch cup and simultaneously in a new manner bodily combined in the interior of the intermediate piece in such manner that back flashing of the flame is in the safest manner taken up by the catch cup and the non-return valve is closed instantaneously. The known cooling bodies are in a new manner arranged in an intermediate piece provided with safety valves. As a result of this arrangement the overpressure prevailing in the piping on back flashing of the flame may be discharged through the safety valves. Moreover the known cooling body is combined with the non-return valve in a new manner and the arrangement is such, that on back flashing of the flame the non-return valve can only come into contact with the cooled back flashing gases. At the same time the known cooling body is formed in a new manner as guide for the non-return valve. Furthermore the known cooling body and the non-return valve with catch cup are in a new manner so combined in the intermediate piece, that in the direction of flow the non-return valve lies in front, the catch cup, however behind the cooling body. In this arrangement the back flashing flames not only directly impinge upon the catch cup and cause instantaneous closing of the non-return valve, but the latter remains also constantly in cool gases. All combinations are connected in a new manner to a device counting the back flashings of the flames, whereby the opening movements of one of the safety valves are transferred to an indicating device arranged 11

for instance at the driver's seat of a motor car or an aeroplane.

During the operation of explosion motors condensations may, under special service conditions, for instance, generally in a severe winter, occur in the pipings feeding the gas mixture. To give a special example: In heavy freight cars often heavy petrol is used to reduce the fuel costs. For starting purposes and idle run of the motor light petrol is used and during the operation the motor is automatically or by hand adjusted to be charged with heavy petrol. This mixture of heavy petrol and air tends very much to condense in the suction pipes.

To prevent such condensations the devices described above for stopping the back flashing of the flames may be provided with a jacket for supplying said devices with a heating medium. To obtain a more intensive and a more perfect heating suitable members of the construction (for instance the arm-cross and the absorption bodies) are used for this purpose and accordingly made hollow. Of course, special perforations of the casing could also be provided. The heating is effected in known manner by the cooling water of the motor or by the exhaust gases. This method of heating is preferably used, if the motor operates with heavy oils having a higher boiling point. A distance thermometer is employed for controlling the most favorable heat condition of the fuel used. For regulating the heat supply a throttle valve is arranged in the pipings of the heat carrier. The heating of the device may also be obtained in a known manner by electricity and this directly by surrounding the casing of the device with a heating element. This manner of heating may, however, also be effected indirectly by electrically heating a heat carrier which in turn effects the heat exchange. The heating by electricity also allows regulating of the heating conditions in wide limits.

In the accompanying drawing one mode of construction of the device according to the invention is shown by way of example.

Fig. 1 is a longitudinal section on line I—I of Fig. 2 and

Fig. 2 is a plan view of the new device. As shown in Fig. 1, the known intermediate piece α is, by means of the joints b and c , connected to the piping supplying the gases or gas mixture in such a manner, that the gases normally flow in the direction from c to b . The known protecting nets d^1 , d^2 are arranged in the new manner in the joints of the intermediate piece. In this piece α are arranged the known safety valves n^1 , n^2 at the openings of which protecting nets are provided. A known arm cross arranged in a new manner is the great

cross section of the intermediate piece, or alternately a known cooling body e , constructed, however, in a new manner, serves as a bearing for the parts i , g , h , k , m of the non-return valve. The valve head i is in a new manner formed as a perfect cup and connected by means of its spindle g in a new manner to the known catch cup h . The valve head i and the catch cup h are in the interior of the intermediate piece bodily and advantageously so combined, that back flashings of the flames directly act upon the catch cup. The spring k which, in case a catch cup is not used, bears against a washer fixed to the spindle, is just strong enough, to carry the weight of the movable parts i , g , h . By means of telescoping sleeves the spring k is protected against the action of the hot back flashing gases. Without affecting the tension of the spring, the position of height of the valve head i with regard to the valve seat may be adjusted by means of the threaded nipple m . The cooling body e , known per se in different constructions, may also, but in a new manner, be arranged alone in the intermediate piece α provided with safety valves n^1 , n^2 , so that the overpressure produced by back flashings of the flames may be discharged at once through the safety valves. In all combinations one of the safety valves, for instance the valve n^2 , is connected by means of a Bowden wire to an indicating device, shown diagrammatically in Fig. 1. This indicating device substantially consists of a counting work 1, driven by the shaft 2 upon which is fixed the ratchet wheel 3. The pawl 4 is pivotally mounted upon the pin 5 and is pressed by a spring 6 under light pressure against the ratchet wheel 3. The pawl 7 is pivoted upon the pin 5^a and is also pressed against the ratchet wheel 3 by a spring 6^a. The pawl 7 may be moved in a straight line and by this movement the wheel 3 is turned. The Bowden wire o transfers the movement of one of the safety valves upon that part of the pawl 7 which may be shifted in a straight line and which is always returned by the spring 8.

The operation of the different combinations will be explained by the following description:

The unobstructed flow of the gases or gas mixture is favored by the convex faces of the cups h and i directed towards the direction of flow as well as by the arm cross, or in place of this by the cooling body e having a correspondingly free area of passage which cross or which cooling body e being arranged in the great cross section of the intermediate piece α .

On back flashings of the flames, a direct contact of the igniting flames with the fresh gases is prevented by the protecting nets d^1 , d^2 . The back flashing of the flames acts

upon the concave surface of the valve head *i* or the catch cup *h* which is forced backward, causing an instantaneous closure of the valve. The burning back flashing gases are by passing through the cooler *e* cooled to a harmless temperature. With all combinations the overpressure produced on back flashings of the flames escapes through the safety valves *n*¹, *n*², while at the same time one of them, for instance the valve *n*², transfers its movements by means of the Bowden wire *o* upon the indicating device.

In any of the constructions described above a casing or jacket *p* may surround the intermediate piece *a*. This jacket *p* is provided with joints *q* and *r* for connection to a circulating system of a heating medium. The heating medium may flow through the space formed between the casing *a* and the jacket *p* only, or, if desired, parts arranged inside the piece *a* may be made hollow and be connected to the said space, so that the heating medium also flows through these parts.

A heat carrier, cooling water which has been heated by use, or exhaust gases, or an electrically heated carrier is introduced by the joint *q* circulates in the space between the piece *a* and the jacket *p* and leaves the device by way of the joint *r*. The intermediate piece *a* is therefore constantly heated, so that condensing of parts of the mixture at the inner surfaces of the piece *a* is absolutely prevented. Moreover by a corresponding regulation of the circulating amount of the heat carrier the gas mixture normally passing through the piece *a* is subjected to an additional heating, so that even in a severe winter the new device may be used not only without any draw-backs, but moreover the advantage of heating the gas mixture is obtained together with the protection against back flashings. This means increased utilization of the fuel that is also increased economy in operation.

Of course, many modifications may be made in the construction and arrangement of the parts of the device without departing from the spirit of the invention.

50 What I claim is:

1. In a device for stopping back flashings of the flames in pipings for feeding gases or gas mixtures in combination, an intermediate piece having a greater cross section than the piping arranged in said piping, protecting nets at the joints of said piece, safety valves carried by said intermediate piece, a device operatively connected to one of said safety valves for counting and indicating the back flashings of the flame, a member surrounding the casing of said intermediate piece and means for supplying heat to said member for the purpose of heating the whole apparatus.

65 2. In a device for stopping back flash-

ings of the flames in piping for feeding gases or gas mixtures in combination, an intermediate piece having a greater cross section than the piping arranged in said piping, a cup-shaped non-return valve in said piece, balanced in its weight by a spring and guided by its spindle passing through an arm cross fixed in said piece, protecting nets at the joints of said piece, safety valves carried by said piece, a device operatively connected to one of said safety valves for counting and indicating the back flashings of the flame, a member surrounding the casing of said intermediate piece and means for supplying heat to said member for the purpose of heating the whole apparatus.

3. In a device for stopping back flashings of the flames in pipings for feeding gases or gas mixtures in combination an intermediate piece having a greater cross section than the piping arranged in said piping, a cup shaped non-return valve balanced in its weight and guided in said piece, a catch cup carried by the free end of the spindle of said valve, protecting nets at the joints of said piece, safety valves carried by said piece, a device operatively connected to one of said safety valves for counting and indicating the back flashings of the flame, a member surrounding the casing of said intermediate piece and means for supplying heat to said member for the purpose of heating the whole apparatus.

4. In a device for stopping back flashings of the flames in pipings for feeding gases or gas mixtures in combination, an intermediate piece of greater cross section than the said piping arranged in said piping, a cooling body carried inside said piece, a sliding cup shaped non-return valve balanced in its weight and arranged in the direction of flow of the gas mixture in front of the said cooling body, protecting nets provided at the joints of the said piece, safety valves carried by said piece, a device operatively connected to one of said safety valves for counting and indicating the back flashings of the flame, a member surrounding the casing of said intermediate piece and means for supplying heat to said member for the purpose of heating the whole apparatus.

5. In a device for stopping back flashings of the flames in pipings for feeding gases or gas mixtures in combination, an intermediate piece of greater cross section than the piping arranged in said piping, a cooling body in said piece, a cup shaped non-return valve balanced in its weight and sliding in an adjustable nipple carried by said cooling body, a catch cup carried by the free end of the spindle of said valve, protecting nets at the joints of said piece, safety valves carried by said piece, a device operatively connected to one of said safety valves for counting and indicating

the back flashings of the flame, a member surrounding the casing of said intermediate piece and means for supplying heat to said member for the purpose of heating the whole apparatus.

6. In a device for stopping back flashings of the flames in pipings for feeding gases or gas mixtures in combination, an intermediate piece having a greater cross section than the piping arranged in said piping, safety valves carried by said piece, a

cooling body, a device operatively connected to one of said safety valves for counting and indicating the back flashings of the flame, a member surrounding the casing of said intermediate piece and means for supplying heat to said member for the purpose of heating the whole apparatus.

In testimony whereof I have affixed my signature.

CHRISTEL SCHRAUB.
